(57) **CLAIM**

The ornamental design for a floor tile, as substantially shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is front perspective view of the floor tile showing the new design thereof.

FIG. 2 is a rear perspective view of the floor tile shown in FIG. 1.

FIG. 3 is a top plan view of the floor tile.

FIG. 4 is a bottom plan view of the floor tile.

FIG. 5 is a first-side view of the floor tile.

FIG. 6 is a second-side view of the floor tile.

FIG. 7 is a third-side view of the floor tile.

FIG. 8 is a fourth-side view of the floor tile.

FIG. 9 is an enlargement of the encircled corner area in the side view of the floor tile shown in FIG. 8; and,

FIG. 10 is an alternative embodiment of the floor tile in which the top of the tile has a color, represented in the figure as cross-hatching, which is different than the color of the bottom of the tile.

The tile edges visible in FIGS. 5-8 each have an identical beveled edge as shown in the enlarged exemplar view depicted in FIG. 9. The cross-hatching depicted in FIG. 10 is not surface ornamentation but represents a color, which is different than the color of the bottom portion of the tile. Although applicants claim, in FIG. 10, a tile having different colors on the top and bottom of the tile, with the treads sharing the same color of the bottom of the tile, no claim is made to any specific color.

The broken lines form no part of the claimed design.
